LEWIS B. ALLEN, OF BOSTON, MASSACHUSETTS.

BENCH-STOP.

1,070,938.

Specification of Letters Patent. Patented Aug. 19, 1913.

Application filed May 8, 1912. Serial No. 695,903.

To all whom it may concern:

Be it known that I, LEWIS B. ALLEN, a citizen of the Dominion of Canada, residing at Boston, in the county of Suffolk and 5 State of Massachusetts, (whose post-office address is 212 Pleasant street, Boston, Massachusetts,) have invented certain new and useful Improvements in Bench-Stops, of which the following is a specification.

10 My invention relates to the mechanism used upon the work benches of carpenters, joiners, pattern makers, cabinet makers, wood carvers, etc., for holding firmly pieces of wood of various sizes and forms so that 15 they may be conveniently worked upon by planes, chisels and similar tools.

My invention consists of a forward stop, commonly called a "bench stop," a horizontal back stop for the top of the bench, and 20 a side stop for the front edge of the bench.

My objects are, first, to provide an easily adjusted and readily locked forward stop that when adjusted will be absolutely rigid in resisting any pressure that may be 25 brought to bear upon it in the use of ordinary tools; second, to provide a horizontal back stop capable of securely holding the rear end of a piece of lumber to be worked upon when lying flat upon the work bench; 30 and third, to provide a back stop for the front edge of the bench, capable of securely holding a piece of lumber placed on edge, at the front of the work bench, its forward end resting against any ordinary stop projecting 35 from the front edge of the work bench. I accomplish these objects by means of the mechanism illustrated in the accompanying drawing, in which—

Figure 1 is a side elevation of my device; 40 Fig. 2 is a cross section on the line α α , showing the construction of the back stop; Fig. 3 is a top view of the supporting case of the forward stop; Fig. 4 is a top view of the forward stop proper; Fig. 5 is a plan 45 and Fig. 6 an edge view of the holding cam for the forward stop; Fig. 7 is a plan and Fig. 8 an edge view of a modified holding cam for the forward stop; Fig. 9 is a plan, and Fig. 10 an edge view of the back stop 50 lever.

Similar letters refer to similar parts in the several views.

Referring to Figs. 1 and 2, A is a portion of an ordinary work bench, having a groove 55 α along its front edge, and being provided with a vertical forward stop B, of any

ordinary construction, fixed to the front edge of said bench.

My device for a forward stop consists of a cylindrical metal holder C passing down through the bench top at an angle, preferably of 45 degrees. It is secured in place by the screw c. Through this holder is a semi-circular hole adapted to receive the forward stop D of similar form; while 60 I prefer this form of cross section it may be of some other form equally rigid. The upper end of this stop is cut at such an angle that when in place its upper surface will be parallel to the bench top. The sharp 65 edge thus formed is provided with teeth as shown at d.

The stop D may be adjusted to any desired height above the bench top and firmly secured by the lever E, pivoted by the 70 rivet e. This lever may be made in either 75 of two forms shown. First, as in Figs. 5 and 6, in which the depression b provides a friction surface which holds it in position for securing the stop D, as shown in Fig. 1. 80 The second form is shown in Figs. 7 and 8, in which the circular portion is formed into a side cam as shown at f for the purpose of providing sufficient pressure on the stop D. In either case the lower end of this lever is 85 bent at right angles, as shown at g for the purpose of preventing the stop D from dropping out when the pressure of the lever E is released.

My device for a combined back stop on 90 the top and front of the bench consists of an angle plate F whose horizontal part projects into the groove α of the bench top, which is the preferable form, although if 95 the bench top projects in front, over the bench frame, the angle plate may project back under the bench top, and the groove will not be necessary. Outside of this is the angle plate G. These two angle plates are secured to each other by the rivet h 100 which also forms the pivot for the eccentric lever H. This lever has a circular boss formed upon it which fits into a hole in the angle plate G, the pivot h passing eccentrically through this boss, forming an 105 eccentric by means of which the angle plates F and G may be drawn together, thus providing means for clamping the back stop device at any desired point along the length of the work bench A. The eccentric lever H 110 is shown in Fig. 1 in its clamped position. Its position when released is shown in

dotted lines. Upon the top of the angle plate G is pivoted the back stop lever J by the rivet *l*. Upon its front end is formed the knife-edged eccentric portion *j* adapted to cut into the end of a piece of lumber K as at *j*, Fig. 1, and hold the same firmly against the forward stop D. The lever J is formed with a slight offset so as to carry the upturned thumb extensions below its general level. The toothed portion *m* of the lever J extends beyond the front line of the bench top and is adapted to hold a piece of lumber whose forward end is placed against the stop B, and whose rear end is engaged by the toothed portion forced into it by swinging the free end of the lever J to the front. A piece of lumber L, secured in this manner is shown in dotted lines in Fig. 1.

10 The usual forms of forward bench stops has been such that they frequently became loosened and the toothed points forced upward by the pressure against them, thereby endangering the cutters of the workman's planes. Proper means have not been provided for conveniently adjusting them as to height, or securing them in the desired position.

25

In my device some of the important advantages are these: First, the forward stop standing at a sharp angle, and supported by a casting rigidly fixed in the bench top, provides a very substantial and rigid stop for all purposes for which it is needed. Second, a piece of lumber however thin, lying flat upon the bench, may be securely held by the forward and back stops. Third, a piece of lumber may be as securely held on edge as though lying flat on the bench.

Having described my invention I claim—

In a back stop for woodworker's benches the combination of a clamp consisting of a top and bottom right angle plate and an eccentric lever adapted to fix said clamp at any point along the front of said bench, and a horizontal lever pivoted to said top plate and having on its front end a knife edged eccentric portion whose highest part is at one side of the center, and a toothed portion lying wholly on the opposite side of the center, substantially as and for the purposes described.

LEWIS B. ALLEN.
